[57] ABSTRACT

A method for preparing a plurality of steaks or similar cuts of meat, as well as hamburgers and other ground meat patties, that consist in first drenching the same in cooking oil to seal the surfaces, preheating one or more of the several items of such a plurality at various temperatures and maintaining all of them at such preheated temperatures during the same time period, seasoning, marinating and otherwise treating all of said items similarly or, selectively, in different manners, and finally broiling or otherwise cooking all of the items under similar cooking conditions for the same cooking period so that all of the items will be cooked to the different consistencies varying with the preheating temperatures and may be served at the same time.

STEAK-PREPARING AND BROILING METHOD

BACKGROUND OF THE INVENTION

In restaurant service, especially where groups of people are to be served with steaks, the preparation and cooking times vary according to the consistency or degree of cooking desired by the different people of such groups, some desiring their steaks rare, others well-done, and still others medium-cooked, or between the above-mentioned degrees of cooking. So that serving time may be conserved, all of the steaks that have been cooked to the requested rarer consistencies must wait for the steaks that require most cooking time, i.e., those that are on the well-done side. Under such circumstances, complaints that such steaks are cold frequently follow. The steps of precooling at various levels of heat and then broiling or otherwise cooking for the same time period under identical heating conditions, will enable all of the steaks served to a group of people to be started together and finished ready for serving at the same time; yet each steak will be at the consistency desired.

It is recognized that warming or heating plates or counters are being used to keep waiting food warm or, at least, to slow the cooling thereof before the same is served; but, insofar as keeping steaks hot, such means are not entirely satisfactory.

SUMMARY OF THE INVENTION

A method consisting of the steps of precooling a plurality of steaks for approximately the same time period at varying levels of temperatures substantially lower than broiling temperature, and then broiling all of said precooling steaks under the same broiling conditions during the same time period, so that all of the steaks are ready to be served at the same time yet will be cooked to particular consistencies, in the range between rare and well-done, as ordered. In addition to the above cooking steps, the method may entail the step of drenching in oil to seal in juices before preheating, and the step of seasoning and/or marinating before broiling.

An object of the invention is to provide a steak-cooking method to improve restaurant service and also reduce the costs attending said service, by starting the cooking process of a plurality of steaks, individually ordered to the tastes and desires of the patrons, all at the same time and completing the cooking process of said steaks simultaneously, the same being cooked to the respective consistencies as ordered.

Another object of the invention is to provide a steak-cooking method as above, and having the additional advantage of enabling the serving of a plurality of steaks while the same are still hot.

This invention also has for its object to provide a novel, economical and convenient method or process of superior utility.

The invention also comprises novel combinations of method steps, which will appear more fully in the course of the following description of the present method or process, the same being based on the accompanying drawing. However, the following specification merely discloses one embodiment of the present invention, and the same is given by way of example only.

BRIEF DESCRIPTION OF THE DRAWING

The FIGURE is a semi-diagrammatic view of means for precooling steaks according to the invention.

DESCRIPTION OF THE PREFERRED EMBODIMENT

In this disclosure and in the claims, the term "steaks" in addition to beefsteaks, includes the various cuts of beef commonly called "steaks" and also such other forms thereof as roasts, hamburgers and ground beef — in fact, any items of meat that are prepared to the different consistencies in the range between rare and well-done. Also, the term "-precooling" is intended to define any preheating to raise the temperature of frozen steaks, as well as those at room temperature and those that are refrigerated but not frozen, to a predetermined temperature.

The present steak-preparing and broiling method consists of the essential steps of precooling and broiling and the optional steps of sealing in the juices in the steaks before precooling and of seasoning and/or marinating before broiling.

5 The drawing shows a preferred means for precooling the steaks, the same comprising a hot plate 5, a number of heating units 6 beneath said plate, an electric circuit 7 connecting each heater unit 6 to an electric line 8, said circuits being preferably connected in parallel across said line, and a thermostat or a rheostat 9 in each circuit 7 which may be individually set to bring each unit 6 to a temperature that would precool a steak 10 disposed on the hot plate 5 and above each heater unit to a predetermined consistency. A thermostat 11 may be provided in each circuit 7, the same being normally closed and opening only when the temperatures of the hot plate 5, serviced by the various heater units 6, reach the respective temperatures for which set.

Assuming that a waiter is given an order for five similar steaks, sirloin steaks for instance, and the same are respectively ordered to be broiled to different consistencies, as rare, medium-rare, medium, medium-well and well-done, and further assuming that five heater units 6 are provided in conformance with the desired five different degrees of precooling, the rheostats 9 are adjusted so the units 6 will generate five different temperatures to subject the portions of the hot plate 5 thereabove, or an individual hot plate above each unit 6, accordingly, to the heat given off by the heater units. The settings of the rheostats will be different for steaks stored in freezers or those kept under refrigeration. For frozen steaks, the rheostats 9 of the different circuits 7 may be set, respectively, at a low of 60° F. and a high of 100° F., with each of the three circuits in between at temperatures within this range as set by the respective thermostats or rheostats 9. The temperatures and the range thereof may be changed for steaks of different thickness, but in any case the same should be set so that, during the same period of time, say 5 to 15 minutes, the five steaks will be heated approximately to the temperatures of the respective heater units that are precooling them. The above temperatures are given by way of example; in any case, the temperatures for precooling should be materially lower than 200° F.

20 In the example given, at least one intermediate temperature in the range above given may be selected according to the degree of rareness desired. Accordingly, such selection will be for a temperature between the low and intermediate temperatures of the stated range for rarer precooling, and for a temperature between such intermediate temperatures and the high temperature of said range for less rare precooling.

25 40 45 50 55 60 65 70 75

As hereinabove indicated, the steaks may first be drenched in a cooking oil which may comprise melted butter, olive oil, or any of the oils, including various vegetable oils commonly used, to effect sealing of the surfaces of the steaks. Whereas in the past, broiling heat was used for this purpose, in the present case the substantially lower precooling heat is used and has served to retain the oil rather than evaporating it, thereby providing improved sealing-in of the natural juices of the steaks.

The steaks may be kept under the low precooling heat until it is advisable to subject them to broiling heat. This will depend on when serving of the cooked steaks will take place.

Before placing the steaks in a broiler or a plurality of broilers, the same may be marinated in any of the usual ways and/or seasoned in various common ways. In any case, the steaks are subjected to the same broiling conditions for the same time period, which may be set for 5 to 15 minutes. The broilers may be of the type that apply broiling heat to one side and, therefore, require the steaks to be turned, or they may provide for applying broiling heat to both sides at the same time. Regardless of the type of broiler used, the application of heat to the steaks should be the same for all of them, for the purpose of finish-broiling so that the different steaks, according to the degree of application of precooling heat, will be broiled to the respective consistencies according to the precooling temperatures. The steaks will be ready for serving

at the same time: those precooked at the lower temperatures will be rarest; those precooked at the higher temperatures, the most well-done; and the others in the medium range, as above indicated.

While the foregoing discloses what is now contemplated to be the best mode of carrying out the invention, the same is, of course, subject to modification without departing from the spirit and scope of the invention.

I claim:

1. A method for preparing a plurality of steaks that are to be simultaneously served and broiled to the state of rare or well-done or in between such consistencies as ordered, that consists in:

simultaneously precooking said plurality of steaks for the same period of time within the range of 5 to 15 minutes, those steaks to be rarest at about the lowest temperature of a range between about 60° F and 100° F, those steaks

to be most well done after final broiling at about the highest temperature of said range, and those steaks to be broiled to consistencies between rare and well-done at temperatures between the low and high of said range, and thereafter

simultaneously broiling said precooked steaks all under the same temperature conditions for the same period of time.

2. A steak-preparing method according to claim 1 in which the steaks are drenched in cooking oil before precooking to seal in the juices thereof.

3. A steak-preparing method according to claim 1 in which the steaks are seasoned and/or marinated between the precooking and broiling steps.

4. A steak-preparing method according to claim 2 in which the steaks are seasoned and/or marinated between the precooking and broiling steps.
